FLUID SAMPLE COLLECTOR FOR RADIOACTIVE WASTE AND OTHER CONTAMINANTS

Karl Aurand, 94 Am Schlachtensee, Berlin-Schlachtensee,
Germany, and Julius Bosch, 30 Bahnhofstrasse, Erlan-
gen-Bruck, Germany

Filed June 30, 1961, Ser. No. 65,770

Term of patent 14 years

(Cl. D16—2)

The FIGURE is a bottom perspective view of a fluid sample collector for radioactive waste and other contaminants, showing our new design.

The side not shown is substantially the same as the side shown.

The top of the adjustable float not shown and the uppermost knurled nut which is partially shown are substantially the same in appearance as the bottom of the float and the knurled nut, respectively shown.

We claim:

The ornamental design for a fluid sample collector for

radioactive waste and other contaminants, as shown and described.
